PHONOGRAPH

Original Filed April 1, 1920 2 Sheets-Sheet 2

Fig. 3.

UNITED STATES PATENT OFFICE.

WILLIAM M. VENABLE, OF PITTSBURGH, PENNSYLVANIA.

PHONOGRAPH.

Original application filed April 1, 1920, Serial No. 370,521. Divided and this application filed August 12, 1921. Serial No. 491,656.

To all whom it may concern:

Be it known that I, WILLIAM M. VENABLE, a citizen of the United States, residing at Pittsburgh, in the county of Allegheny and State of Pennsylvania, have invented certain new and useful Improvements in Phonographs, of which the following is a specification.

This invention relates to phonograph apparatus which may be used either for recording or reproducing purposes and it is particularly applicable to phonographs of the disc type.

The present application is a division of my copending application #370,521, filed April 1, 1920.

The principal object of the invention is to provide a simple means for maintaining the soundbox stylus in its correct position with respect to the record without abandoning the use of the fixed pivotal support for the soundbox which has proven so advantageous in practice as to have become almost universally applied. It is the further intention of this invention to provide means to accomplish the foregoing object which can be readily applied to the various types of phonographs already on the market with but little, if any fitting or change. These, together with such other objects as are incident to my invention, or which may appear hereinafter, I obtain by means of a construction which I have illustrated in preferred form in the accompanying drawings, wherein:

Fig. 1 is a plan view of an apparatus embodying my improvements showing parts of the phonograph broken away; Fig. 2 is a side elevation of the apparatus illustrated in Fig. 1; Fig. 3 is a plan view of my improved apparatus illustrating the invention as it might conveniently be applied to that type of phonograph known on the market as the Victrola; Fig. 4 is a side elevation of the apparatus illustrated in Fig. 3.

In Figs. 1 and 2 I have illustrated an apparatus which is particularly useful in connection with the recording of records but which can also be used for purposes of reproduction although for the latter purpose

I prefer to use the constructions illustrated in Figs. 3 and 4. By means of a suitable clamp 1, I secure to some portion of the phonograph cabinet 2 a supporting frame 3

which is clamped between the two nuts 4 and 5

threaded to the upwardly projecting standard 6 which is preferably formed integral with the clamp 1. By means of this construction I am enabled to fix the frame 3 firmly to the phonograph cabinet at any desired elevation within reasonable limits. In place of the clamp 1, I may provide other means for securing the apparatus in position, such as mounting it on a heavy base that may be set down within the phonograph cabinet. The inner end of the frame 3 is constructed to provide a pivotal support for the guide bar 7 at the point marked 8 which is positioned, when clamping the frame 3 between the nuts 4 and 5, at a point directly above axis 9 of the turn-table 10. This pivot is a vertical pivot and permits swinging movement of the guide bar 7 while still maintaining it at all times radially disposed with respect to the disc or turn-table.

The soundbox 11 is mounted in a carrier arm 12 which is vertically pivoted at the point 13 to a guide arm 14. The guide arm 14 swings on a pivot 15 located at the outer end of the frame 3. The connection between the soundbox 11 and the carrier arm 12 embodies a horizontal pivot 16 which permits vertical movement of the stylus 17 in order to take care of any irregularities there may be in the record surface 18 or in the mounting of the turn-table 10 on its axis 9. The interior of the soundbox 11 communicates with the trumpet 19, which, as before stated, is particularly designed for recording purposes. The same apparatus could, however, be used for reproducing purposes without change.

In order to obtain the most satisfactory results it is advisable that that point or portion of the soundbox stylus which is cutting the sound groove, if recording, or following it, if reproducing, should be constantly maintained in a plane which is tangent to the groove at the point of contact. In order to accomplish this result without abandoning the swinging support for the soundbox which is used practically universally in reproducing machines I provide the pivotal connection 13 between the soundbox and the swinging guide arm 14. As the guide arm moves inwardly toward the center of the record from the position indicated in dotted lines in Fig. 1, it is necessary to move the soundbox and its carrier a short distance in the reverse direction around the pivot 13.

The point of the stylus 17 should follow substantially the dotted line 20. The connection 21 between the guide bar 7 and the soundbox carrier arm 12 must, therefore, be 5 such as to permit relative radial movement between the two, but at the same time maintain a fixed relation between the two with respect to rotative movement about the pivots 8 and 13.

10 For recording purposes it is necessary to provide a feeding mechanism for the soundbox which I may accomplish by threading the guide bar 7 and by correspondingly threading the point of connection with the 15 soundbox carrier arm 12. By slowly rotating the guide bar the soundbox may be swung inwardly from the outside of the record toward the center. I provide for rotation of the guide bar by projecting it beyond the pivot 8 a short distance and connecting to this projection a pulley 22 which is driven by means of a suitable flexible connection 23 between it and the shaft 24 fixed to which is a friction wheel 25 positioned so 25 as to contact with the periphery of the turn-table 10. The supporting housing 26 for the shaft 24 and the wheel 25 may be made integral with the frame 3 or detachable, as may be suitable or desirable. In this way I 30 combine a feeding mechanism with a guiding mechanism; but it is obvious that I may employ a feed mechanism similar to that described, and yet dispose it with reference to the disc in a relation other than radial provided I do not make the guide mechanism depend upon it, employing instead an independent guide mechanism such as is illustrated, for example, in Figs. 3 and 4 to be 35 described hereinafter.

40 For reproducing purposes the same kind of apparatus could be used without change although when so used it is unnecessary to provide the threaded connection between the guide bar 7 and the carrier arm 12. A sliding connection might be substituted with 45 equally good results inasmuch as in reproducing the soundbox is carried from the outer edge of the record to the inner edge by the needle following the sound groove. It 50 is also possible in a reproducing machine to fix the carrier arm 12 to the outer end of the guide bar 7 and to provide a sliding connection in the pivot 8.

55 In Figs. 3 and 4 I have illustrated two embodiments of the invention which are specifically useful in connection with machines which are designed for reproducing purposes only. I have illustrated it as it could be conveniently applied to that type of 60 phonograph known as the Victrola which is designed for playing lateral cut records.

65 In these figures; namely Figs. 3 and 4, the swinging guide arm is represented by the tone arm 14'. Its pivotal support 15' corresponds to the pivot 15 of Figs. 1 and 2. The

soundbox 11' carried by the arm 12' is connected to the guide or tone arm by means of the vertical pivot 13' corresponding to the vertical pivot 13 in Figs. 1 and 2. At this vertical pivot 13' there is fixed to the carrier 70 arm 12' the supplemental arm 27 to the outer end of which is pivoted one end of the guide bar 7' by means of the pivot 21'. The other end of the guide bar is connected to a fixed support by means of 75 the pivot 8' which corresponds to the pivot 8 of Figs. 1 and 2. By this simple construction the point of the stylus 17' can be maintained at all positions of the guide arm 14' in its correct position with respect to 80 the groove in the record 18 in which it is traveling. To this end the proportion of the various parts are geometrically worked out and the various points of pivotal support 85 properly located. When the soundbox is placed upon the outer edge of a record the parts will assume the positions indicated in dotted lines in Figs. 3 and 4, and when the record has been played the parts will assume the positions indicated in full lines in 90 the same figures. As the guide arm 14' swings inwardly toward the center of the record the soundbox carrier arm 12' will be moved in the opposite direction on its pivot 13' in a manner similar to that which occurs 95 in the construction illustrated in Figs 1 and 2. It will be readily seen that this arrangement of the parts 14' and 7' is preferable to that of the parts 14 and 7 of Figs. 1 and 2 because it requires much less accurate fitting 100 and insures a steadier motion at the pivot 13. In practice I prefer it for that reason as well as because it leaves the space above the turn-table unobstructed for placing and for removing records and record blanks. 105

The arrangements shown in Figs. 3 and 4 do not require that the pivot 8' be located directly above the axis of the turn-table as in Figs. 1 and 2. This guide arm feature of my invention can be applied to the Victrola without other modifications than those necessary to provide the vertical pivot at 13' and the parts 7' and 27 pivoted as described. In talking machines as hitherto made there has been but one vertical pivot provided and 110 that is the one at 15' around which the guide or tone arm 14' swings. Consequently the stylus 44, as it moves inwardly over the surface of the record, makes a continually changing angle with respect to the groove 115 in which it is traveling, the total amount of variation ranging anywhere from 10° to 20°. 120

What I claim is:

1. In disc phonograph apparatus, the combination of a soundbox with a stylus, a vertically pivoted guide arm therefor, a vertical pivot connecting the soundbox to the guide arm, and a feeding mechanism for the soundbox, said feeding mechanism also operating to move the soundbox on its pivot to 130

maintain the stylus axis in a plane substantially tangential to the direction of rotation of the disc at the point of stylus contact with said disc.

5 2. In disc phonograph apparatus, the combination of a soundbox, a vertically pivoted guide arm therefor, a vertical pivot connecting the soundbox to the guide arm, a feeding mechanism for the soundbox disposed 10 transversely of the disc, and a vertically pivoted support for the feeding mechanism.

3. In disc phonograph apparatus, the combination of a soundbox, a guide arm therefor pivoted to provide swinging movement 15 across the disc for the soundbox, a pivotal connection between the soundbox and the guide arm for providing the box with swinging movement with relation thereto similar to that of the arm, a feed screw for moving 20 the guide arm and box across the disc, pivoted to swing like the guide arm, and means for revolving the screw.

4. In disc phonograph apparatus the combination of a soundbox, a carrier for the 25 box vertically pivoted to a swinging arm, a guide bar for the carrier, a fixed support for said bar to which it is pivotally connected, and a threaded connection between the carrier and the guide bar.

30 5. In disc phonograph apparatus the combination of a sound box, a carrier for the box vertically pivoted to a swinging arm, a guide bar for the carrier, a fixed support for said bar to which it is pivotally connected, 35 and a connection between the carrier and said bar which maintains a fixed alignment between said members but permits movement of the carrier toward or away from the pivotal connection for the guide bar.

40 6. In disc phonograph apparatus, the combination of a sound box, a vertically pivoted guide arm therefor, a vertical pivot connecting the sound box to the guide arm, a feeding mechanism for the sound box disposed 45 transversely of the disc, a vertically pivoted support for the feeding mechanism, a stylus, and means cooperating with the vertical pivot connecting the sound box to the guide arm for maintaining the axis of 50 said stylus in a plane substantially tangential to the direction of rotation of the disc at the point of stylus contact with said disc.

55 7. In disc phonograph apparatus the combination of a swinging arm, a soundbox pivoted thereto for similar swinging movement, and a radially disposed guide bar for the soundbox pivoted to a fixed support, said guide bar pivot being directly above 60 the center of the disc and permitting swing-

ing movement of the bar in a plane substantially parallel to the disc.

8. A unitary feeding and recording mechanism for a disc phonograph sound box comprising in combination a supporting member detachably mounted on the phonograph cabinet, a guide arm vertically pivoted to the supporting member, a carrier for the sound box vertically pivoted to the guide arm, a guide bar for the carrier vertically pivoted to the supporting member, a threaded connection between the guide bar and the carrier, and means for turning the guide bar in said threaded connection whereby to move the sound box across the disc.

9. A unitary feeding and recording mechanism for a sound box on a disc type machine having a turntable, comprising in combination a supporting member mounted on the phonograph cabinet, a guide arm for the sound box pivoted to the supporting member, a feeding mechanism for the sound box carried by the supporting member, and means actuated by the turn-table for operating the feeding mechanism, said means also being carried by the supporting member.

10. A unitary feeding and recording attachment for a disc phonograph sound box comprising in combination a supporting member mounted on the phonograph cabinet, a carrier for the box pivotally mounted on the supporting member to swing above the disc, a sound receiving trumpet secured to the carrier, and a feeding mechanism for moving the carrier also secured to the detachable supporting member, said box being horizontally pivoted to said carrier at the terminus of the trumpet.

11. A unitary recording mechanism for a disc type phonograph having a turntable, comprising in combination an attaching member mounted on the phonograph cabinet, a guide arm pivoted to the attaching member to swing horizontally over the turntable, a recording sound box and sound receiving trumpet sustained on said guide arm, a feed screw pivoted to the attaching member to swing horizontally over the turntable, a threaded member engaging said screw to cause swinging of the sound box and guide arm when the screw is rotated, and means driven by the turntable for revolving the screw, said means being carried by the attaching member.

In testimony whereof, I have hereunto signed my name.

WILLIAM M. VENABLE.
